[57] CLAIM

The ornamental design for a fire resistant container,
substantially as shown.

DESCRIPTION

FIG. 1 is a perspective view of a fire resistant container
showing my new design;

FIG. 2 is an end view thereof as seen from the end
opposite that shown in FIG. 1;

FIG. 3 is a side elevational view thereof;

FIG. 4 is a top plan view thereof; and

FIG. 5 is a bottom plan view thereof.
